UNITED STATES PATENT OFFICE.

ELMER HEDGLIN, OF SCRANTON, PENNSYLVANIA.

ROTARY VALVE FOR INTERNAL-COMBUSTION ENGINES.

Application filed June 2, 1927. Serial No. 198,607.

The present invention relates to a rotary valve structure for internal combustion engines and has for its principal object to provide a rotary valve of exceedingly simple construction which is of a compact nature, comparatively inexpensive to construct, durable, thoroughly efficient and reliable in its operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of the rotary valve structure embodying the features of my invention,

Figure 2 is a longitudinal vertical section therethrough,

Figure 3 is a fragmentary perspective view showing one end of the valve proper with portions broken away,

Figures 4 and 5 are vertical sections taken substantially on the lines 4-4 and 5-5 of Figure 2, respectively,

Figure 6 is a sectional view through the valve structure showing the same midway between exhaust and intake,

Figure 7 is a similar view showing the valve at the end of the intake stroke of the piston,

Figure 8 is a similar view showing the valve when the piston is about to be driven on its power stroke,

Figure 9 is a similar view showing the beginning of the exhaust stroke.

Referring to the drawings in detail, it will be seen that the numeral 5 denotes a cylinder block in the present instance, provided with fixed cylinders 6. The numeral 7 denotes the cylinder head which is in the form of a cylindrical casing 8 jacketed for cooling purposes as at 9. This cylindrical casing or cylinder head is bolted on the cylinder block 5 as at 10 or in any other suitable manner. End heads 11 and 12 are provided for the cylindrical casing 8 and are bolted in place as are indicated at 13 and 14 respectively or held in place in any other suitable manner. The numeral 15 denotes a shaft which is journaled in the heads 11 and 12 to be disposed coaxially through the cylindrical casing and has

mounted thereon the valve proper which is indicated generally by the letter V. Suitable packing such as rings or the like may be disposed between the valve V and the casing 8 as will be quite apparent to those skilled in this art. The shaft 15 is driven by a chain and sprocket mechanism 16 from the crank shaft of the engine (not shown) so that the shaft 15 rotates at one-half crank shaft speed.

The valve V comprises a sleeve 17 having ends 18 integral therewith or welded thereto, to mount the sleeve concentrically about the shaft 15. A pair of partitions 19 divide the valve into two portions which are of identical construction, one portion being for three cylinders and the other portion for the remaining three cylinders. Each half of the valve has its sleeve portion provided adjacent its ends 18 with a semi-circular opening or slot 20 constantly in registry with an intake passage or groove 21 formed in the casing and communicating with intake manifold 22 in any suitable manner. Adjacent to the slot or opening 20 the sleeve is formed with another semi-circular slot 23 which is constantly in communication with channel or groove 24 formed in the casing 8 and communicating with an exhaust manifold 25 in any suitable manner.

Adjacent to the slot or opening 20 the sleeve is formed with another semi-circular slot 23 which is constantly in communication with channel or groove 24 formed in the casing 8 and communicating with an exhaust manifold 25 in any suitable manner. The exhaust channel 24 is wider than the intake channel 21 and the slot 23 will be correspondingly larger than the slot 20.

A transverse partition 26 is disposed between the intake and exhaust portions of the sleeve. A longitudinal partition 27 is in the intake compartment and is disposed diametrically from one end of the slot 20 to the other end thereof and a similar partition 28 is disposed in the exhaust compartment extending from one end of the slot 23 to the other end thereof. The partitions 27 and 28 are perpendicular to each other. The partition 26 has openings 30 and 31. The opening 30 leads to the chamber a in the exhaust compartment while the opening 31 leads to the chamber b in the intake compartment of the sleeve.

Partitions 32 and 33 divide the remaining portion of this half of the sleeve into three cylinder compartments and the casing has openings 34 to communicate the cylinders with these cylinder compartments as the valve rotates. Each compartment has

its sleeve portion formed with a pair of approximately 90 degree openings 36 and 37, the former of which is an intake opening and the latter of which is an exhaust opening.

These cylinder compartments are divided by longitudinal diametrically extending partitions 38 to provide exhaust chambers E and intake chambers I. The partitions 32 are 5 provided with openings 39 and 40 communicating the exhaust chamber of one cylinder compartment with the exhaust chamber of the other and the intake chamber of one cylinder compartment with the intake chamber 10 of the other compartments.

The openings 36 and 37 are properly arranged to register with openings 34 so that the engine may operate on the well known four-cycle principle and these openings in 15 one cylinder compartment will be properly arranged with the openings in the other cylinder compartment so that the engine may operate in the desired firing order.

The positions for the different cycles may 20 be followed from an inspection of Figures 6 to 9 inclusive and will be well understood by those skilled in this art without a detailed description. It will be seen that the valve is properly cooled by the jacketing afforded 25 at 9 and yet the intake gases are properly heated by the exhaust gases because of the arrangement of the passages formed by the exhaust and intake chambers of each cylinder compartment of the sleeve valve. Thus great 30 efficiency is attained and there is nothing about the valve for a multiple cylinder engine to get out of order as in comparison with the pocket valves now in common use and the well known Knight sleeve valve.

35 It is thought that the construction, operation, utility and advantages of this invention will now be quite apparent to those skilled in this art. It is apparent that the valve may be adapted to any number of cylinders and still maintain the principle of 40 invention. In fact, the present embodiment of the invention has been disclosed in detail merely by way of example since in actual 45 practice it attains the features of advantage enumerated as desirable in the statement of the invention and the above description. It will be apparent that changes in the details of construction, and in the combination and arrangement of parts may be resorted to 50 without departing from the spirit and scope of the invention as hereinafter claimed or sacrificing any of its advantages.

Having thus described my invention, what I claim as new is:—

1. In a rotary valve structure of the class 55 described, a casing forming a cylinder head and having ports for communication with the cylinders of a cylinder block, a pair of annular passages about the casing forming an intake and an exhaust, and a rotary valve 60 in the casing throughout the length thereof, said valve comprising a cylindrical sleeve, partitions transversely of the sleeve dividing the same into a plurality of compartments, said sleeve having openings communicating 65 with the intake passage, the exhaust passage, and the cylinder ports.

2. In a rotary valve structure of the class described, a casing forming a cylinder head and having ports for communication with the 70 cylinders of a cylindrical block, a pair of annular passages about the casing forming an intake and an exhaust, and a rotary valve 75 in the casing throughout the length thereof, said valve comprising a cylindrical sleeve, 80 partitions transversely of the sleeve dividing the same into a plurality of compartments, said sleeve having openings communicating with the intake passage, the exhaust passage, and the cylinder ports, said compartments being divided by diametrically disposed longitudinal partitions into sections, one for the intake and one for the exhaust.

3. In a rotary valve structure of the class 85 described, a casing forming a cylinder head and having ports for communication with the cylinders of a cylindrical block, a pair of annular passages about the casing forming an intake and an exhaust, and a rotary valve 90 in the casing throughout the length thereof, said valve comprising a cylindrical sleeve, partitions transversely of the sleeve dividing the same into a plurality of compartments, said sleeve having openings communicating 95 with the intake passage, the exhaust passage, and the cylinder ports, said compartments being divided by diametrically disposed longitudinal partitions into sections, one for the intake and one for the exhaust, heads on the ends of the casing, said rotary valve having 100 a shaft extending coaxially therethrough and journaled in the heads.

In testimony whereof I affix my signature.
ELMER HEDGLIN.
